PAPER PULP SCREEN

Wilfred F. Mathewson, Weymouth, Mass.

Application January 26, 1945, Serial No. 574,769

13 Claims. (Cl. 92—35)

1 This invention relates to pulp screens, and it has for one of its objects to provide a novel screen which is capable of an increased output as compared with other screens of the same size.

Another object of the invention is to provide a novel pulp screen which will screen the pulp to a given size of fibre with a high degree of accuracy.

A further object of the invention is to provide a novel means for keeping the screening elements clean and free from accumulated refuse or "rejects."

Still other objects of the invention are to improve generally pulp screens in various ways as will be hereinafter set forth.

In attaining these objects, I have provided a pulp screen in which the screening means is constituted by two parallel walls separated by a small clearance space which is of sufficient size to permit the fine acceptable portion of the unscreened pulp to pass therethrough but which is insufficient in size to permit the coarse material or refuse to pass, one of said walls being provided with a plurality of pockets or grooves, all of which open into the clearance space, and in which the unscreened pulp is delivered by means other than the clearance space to certain of said grooves or pockets, the remaining grooves or pockets being connected by means other than the clearance space to a screened pulp outlet. For convenience I will refer to the grooves or pockets to which the unscreened pulp is delivered as "inlet grooves" or "inlet pockets" and will also refer to the grooves or pockets which communicate with the screened pulp outlet as the "discharge grooves" or "discharge pockets." Both the inlet grooves or pockets and the discharge grooves or pockets communicate with the same clearance space, and in the screening operation, the pulp which is delivered to the inlet pockets tends to flow into the discharge pockets through said clearance space, but as the latter is of a size to permit only the fine acceptable portion of the pulp to pass therethrough and is of insufficient size to permit the coarse material to pass, the result will be that only the fine acceptable portion of the pulp will flow from the inlet pockets to the discharge pockets through said clearance space.

Any coarse unacceptable portion of the pulp which cannot pass through the clearance space will tend to clog the latter, and I have provided novel means for periodically flushing such clearance space to flush out of it any accumulation of coarse unacceptable material.

2 In order to give an understanding of the invention, I have illustrated in the drawings a selected embodiment thereof which will now be described, after which the novel features will be pointed out in the appended claims.

In the drawings:

Fig. 1 is a vertical sectional view of a pulp screen embodying my invention, said section being taken on the line 1—1, Fig. 2.

Fig. 2 is a horizontal sectional view on the line 2—2, Fig. 1.

Fig. 3 is a fragmentary vertical sectional view.

Fig. 4 is a section on the line 4—4, Fig. 3.

Figs. 5, 6, and 7 are fragmentary transverse sectional views through the screening elements illustrating the screening and screen-cleaning operations.

Fig. 8 is an enlarged section on the line 8—8, Fig. 3.

Fig. 9 is an enlarged section on the line 9—9, Fig. 3.

Fig. 10 is a fragmentary view showing the outside of the screening element 8;

Fig. 11 is a fragmentary sectional perspective view showing a portion of the inside of the outer screening element 8, said view showing a section taken through the inlet pockets or grooves 10;

Fig. 12 is a view similar to Fig. 11, but showing the section taken through the outlet pockets or 30 grooves 11.

The pulp screen herein illustrated comprises a casing member 1 herein shown as cylindrical in cross section and which is provided at its upper end with a head 2 having an inlet 3 for the unscreened pulp. Said casing is also provided at its lower end with a base or lower head 4 provided with an outlet 5 for the screened pulp and a second outlet 6 for the tailings or rejects.

The screening means of my improved pulp 40 screen is located within the casing 1 and is constituted by two screen members which present two parallel walls separated from each other by a small clearance space that is of sufficient size to permit the fine acceptable portion of the pulp to pass therethrough but is insufficient in size

45 to permit the coarse unacceptable portion of the pulp to pass. One of these screening members is provided with a plurality of grooves or pockets in its wall which bounds the clearance space, 50 certain of said pockets or grooves having communication with the unscreened pulp inlet 3 and the remainder of said pockets or grooves having communication with the screened pulp outlet 5.

These screen members are shown as cylindrical 55 members arranged concentrically. The two

screen members are constituted by an inner cylindrical member 7 and an outer cylindrical member 8, said cylindrical members having a common axis and thereby being concentric. The outer wall of the inner member 7 and the inner wall of the outer member 8 are spaced apart so as to provide a small clearance space 9 which is of a size to permit the fine acceptable portions of the pulp to pass through but is insufficient in size to permit the coarse unacceptable portions of the pulp to pass.

One of the screen members, the outer member 8 in the present embodiment of the invention, is provided in the wall thereof which bounds the clearance space 9 with a plurality of pockets herein shown in the form of vertical grooves. Some of these pockets have communication with the pulp inlet 3, while the remainder of the pockets have communication with the screened pulp outlet 5. I will preferably arrange these grooves or pockets in circumferential rows and in such a way that every other pocket in any row communicates with the inlet 3 while the other pockets communicate with the screened pulp outlet 5. In other words, the successive pockets or grooves communicate alternately with the inlet 3 and the outlet 5, and all the pockets or grooves also communicate with the clearance space.

The grooves which communicate with the inlet 3, and which for convenience are referred to as "inlet grooves" are indicated at 10, while the other grooves which communicate with the screened pulp outlet 5 and which for convenience are referred to as "discharge grooves" are indicated at 11. Each inlet groove 10, therefore, has on each side thereof a discharge groove 11 and the communication between any inlet groove 10 and the adjacent discharge groove 11 is through the clearance space 9.

These grooves 10 and 11 may extend the full length of the outer member 8, but I will preferably provide said member with a plurality of rows of shorter grooves, each row of grooves extending circumferentially.

The outer screen member 8 is shown as composed of an outer section 12 and an inner section, which in turn is composed of a plurality of annular ring like members 13. The inner face of each ring member 13 is formed with the grooves 10 and 11, and the outer face of each ring member is provided with an annular rib 14 which is secured to the outer section 8 by means of attaching screws 15. The outer section 8 is formed with circumferential bulged portions 16 which with the ring members 13 and the ribs 14 provide a plurality of circumferential chambers 17, 18. The grooves 10, 11 are so formed in each ring member 13 that of any two adjacent grooves, one of them will communicate with an annular chamber 17 while another will communicate with an adjacent annular chamber 18. The grooves 10, 11 are shown as being of progressive depth from one end to the other, the deep end of each groove opening into one of the chambers 17 or 18. Referring for instance to Fig. 3, the ring member 13a has in it the rows of vertical grooves, the grooves 10 opening into the annular chamber 17 while the other grooves 11 open into the annular chamber 18.

Means are provided whereby unscreened pulp may be delivered to the various annular chambers 17 and by which the various annular chambers 18 are connected to the screened pulp outlet 5.

For convenience I will refer to the annular

chambers 17 as "inlet chambers" and to the annular chambers 18 as "discharge chambers."

The unscreened pulp which is delivered to the inlet chambers 17 will pass through the inlet grooves 10 of the various ring members 13 and the acceptable portion of the pulp will pass through the clearance space 9 into the discharge grooves 11, from which the pulp is delivered to the annular discharge chambers 18 and from the latter to the screened pulp outlet 5. The means by which the unscreened pulp is delivered to the annular inlet chambers 17 and the screened pulp is delivered from the discharge chambers 18 to the screened pulp outlet 5 is as follows. The space between the outer screen member 8 and the casing 1 is divided by vertical partitions 19 into a plurality of vertical passageways 20, 21. The casing 1 is provided at its upper end with a transverse partition 22 which has openings 23 therein that communicate with the vertical passages 20 only, so that unscreened pulp may flow from the inlet 3 into said passages 20 only. For convenience, these passages 20 will be referred to as "inlet passages."

The outer section 12 of the screen member 8 is provided with openings 24 in the outer wall of each annular inlet chamber 17, which openings 24 register with the vertical inlet passages 20 and provide communication between said inlet chambers 17 and the inlet passages 20. The lower ends of all the vertical passages 20 are closed by a horizontal partition 25.

The inner screen member 7 is formed with a top 26 which, together with the partition 22, constitutes the bottom of an annular chamber 28 with which the inlet 3 communicates so that the unscreened pulp delivered to the inlet 3 will fill the chamber 28 and flow through the openings 23 into the vertical passages 20 and from these through the openings 24 into the inlet chambers 17. From the inlet chambers 17 the pulp flows through the inlet slots or grooves 10 into the clearance space 9, and the acceptable portion of the pulp will flow through the clearance space 9 around into the discharge grooves or slots 11, which, as stated above, communicate with the annular discharge chambers 18. These discharge chambers 18 communicate with the vertical passages 21 through openings or ports 30 which are formed in the outer section 12 of the screen member 8, and therefore the acceptable portion of the pulp which passes through the clearance space into the discharge grooves 11 will be delivered into the annular chambers 18 and from these into the vertical passages 21. For convenience the vertical passages 21 are referred to as "discharge passages."

The horizontal partition 25 is provided with ports 26, one for each discharge passage 21, which ports lead into the annular sump 27 with which the base 4 is provided and which in turn communicates with the screened pulp outlet 5.

It will be observed that the means by which the unscreened pulp is delivered to the inlet pockets or grooves 10 is separate from the clearance space, and similarly the means provided for delivering the screened pulp from the discharge grooves or pockets 11 to the screened pulp outlet is separate from the clearance space.

It will also be observed that the unscreened pulp is delivered to the clearance space, and the screened pulp is delivered therefrom through pockets or passages formed in the same wall which forms one side of the clearance space.

This screening operation is illustrated in the

Figs. 5, 6, and 7. In these fragmentary sectional views, the unscreened pulp which is delivered to the inlet grooves 10 is shown as flowing through the clearance space 9 into the discharge grooves 11 which communicate with the annular discharge chambers 18.

Any coarse material or unacceptable portion of the pulp such as shown at 31 in Fig. 6 which cannot pass the clearance space 9 will tend to accumulate in the mouth of the inlet groove 10 and thus clog the groove. To prevent any such clogging of the groove, I have provided for periodically flushing out each inlet groove so as to remove therefrom any of the tailings or unacceptable portion of the pulp. This is done by providing the inner screen member 7 with a plurality of openings or slots 32 which extend vertically thereof, and by rotating said inner member within the outer member.

As each slot 32 of the inner member moves past the various inlet grooves 10, the pulp will tend to flow from each groove 10 through the slot 32 into the interior of the inner member 7. This member 7 is open at its bottom and the lower head 4 is provided with a well 33 which communicates with the interior of the member 7 and with the tailings outlet 6.

If at any time any coarse or refuse material such as indicated at 31 tends to accumulate at the open end of any inlet groove 10 as shown in Fig. 6, then when the next slot 32 of the member 7 registers with said clogged slot, the refuse material will be flushed out of the groove through the opening 32, as shown in Fig. 7, and into the interior of the said member 7 from which it will pass through the tailings outlet 6. Each inlet groove 10, therefore, is periodically flushed out by the rotative movement of the member 7 and thus the screen is kept free and in an unclogged condition without the use of any mechanical scrapers or screen-cleaning blades. The slots 32 in the member 7 are made wider at the inner face of said member than at the outer face thereof, thereby providing relatively sharp knife-like edges 43. Such sharp edges act somewhat as knives to help loosen any coarse material or rejects which have dammed up the open side of any inlet slot 10, thus assisting the flushing operation.

Any suitable means will be employed for rotating the inner member 7. In the illustrated embodiment of the invention, the head 28 of said member 7 is provided with a vertical shaft 34 which is mounted in suitable bearings in the head 2 and is provided at its upper end with a worm gear 35 that meshes with a worm 36 on a shaft 37, said shaft being connected by a sprocket chain or belt 38 with a shaft 39 also mounted in bearings in the head 3. The shaft 39 has a pulley 40 thereon which is driven by means of a belt 41 from a suitable motor 42 also mounted on the head 2.

The means for rotating the inner member 7 may be such as to give said member either a continuous rotation or an intermittent or step-by-step rotation. In either case, however, the rotative movement of the inner member brings each slot 32 therein into register with the inlet slots 10 successively so that each inlet slot is subjected periodically to a flushing operation which keeps it clean. The member 7 may be rotated in either direction.

From the above it will be observed that I have herein provided a novel pulp screen in which the screening element comprises two opposed walls

spaced from each other to provide a clearance space sufficient in size to permit the acceptable portion of unscreened pulp to pass therethrough but insufficient in size for the unacceptable portion of such pulp to pass, one of said walls having a plurality of pockets, certain of which communicate with the pulp inlet and the remaining ones of which communicate with a screened pulp outlet, whereby the pulp is screened by passing into the first-named pockets, through the clearance space and into the last-named pockets and from thence to the screened pulp outlet. The pockets or slots 10 and 11 together with the annular chambers 17 and 18 into which the pockets or slots open, provide openings extending through the outer screen member 8, the slots 10 and the chamber 17 constituting inlet openings through which the unscreened pulp flows from the inlet passages 20 on the outside of the screen member 8 into the clearance space 9, and the slots 11 and chambers 18 constituting discharge openings through which the screened pulp flows from the clearance space to the discharge passages 21 that are also situated on the outside of the screen member 8.

The movement of the unscreened pulp into the clearance space and the movement of the screened pulp from said clearance space is therefore through openings in the same wall though in opposite directions. In other words, the unscreened pulp flows through the outer screen member 8 from the outside to the inside while the screened pulp flows through said screen member 8 from the inside to the outside.

It will also be observed that my invention provides a novel construction by which the pockets can be periodically flushed so as to keep them clean from accumulated refuse material.

I claim:

1. A pulp screen comprising a casing having an inlet and a screened pulp outlet, pulp-screening means within the casing comprising two screen members separated by a clearance space of sufficient size for the acceptable portions of unscreened paper pulp to pass therethrough but insufficient in size for the unacceptable portion of such pulp to pass therethrough, one of said members having a plurality of grooves in the face thereof which bounds said clearance space, a portion of said grooves constituting inlet grooves and the remainder of the grooves constituting discharge grooves, means for delivering unscreened pulp from said casing inlet to the inlet grooves, and means providing communication between the discharge grooves and the screened pulp outlet, whereby the pulp is screened by passing from the inlet grooves to the discharge grooves through said clearance space.

2. A pulp screen comprising a casing having an inlet and a screened pulp outlet, pulp-screening means within the casing comprising two screen members separated by a clearance space of sufficient size for the acceptable portions of unscreened paper pulp to pass therethrough but insufficient in size for the unacceptable portion of such pulp to pass therethrough, one of said members having a plurality of grooves in the face thereof which bounds said clearance space, a portion of said grooves constituting inlet grooves and the remainder of the grooves constituting discharge grooves, means for delivering unscreened pulp from said casing inlet to the inlet grooves, means providing communication between the discharge grooves and the screened pulp outlet, said other member being provided with an opening

communicating with the clearance space, and means to move said members relative to each other and in a direction to bring the opening into registry with the inlet grooves successively, whereby when said opening is brought into registry with any inlet groove any coarse material or unacceptable portion of the pulp which has accumulated in said inlet groove is flushed out through said opening.

3. A pulp screen having a casing provided with an inlet for the unscreened paper pulp and an outlet for the screened pulp, two concentric cylindrical screen members located in the casing and providing between them an annular clearance space of sufficient size for the fine acceptable portions of the unscreened pulp to pass therethrough but of insufficient size for the coarse unacceptable portion of such pulp to pass therethrough, one of said members having a plurality of grooves in the face thereof which is adjacent the other member, certain of said grooves constituting inlet grooves and the remainder of the grooves constituting discharge grooves, means by which unscreened pulp from the casing inlet is delivered to the inlet grooves, and means providing communication between the discharge grooves and the screened pulp outlet.

4. A pulp screen having a casing provided with an inlet for the unscreened paper pulp and an outlet for the screened pulp, two concentric cylindrical screen members located in the casing and providing between them an annular clearance space of sufficient size for the fine acceptable portions of the unscreened pulp to pass therethrough but of insufficient size for the coarse unacceptable portion of such pulp to pass therethrough, one of said members having a plurality of grooves in the face thereof which is adjacent the other member, certain of said grooves constituting inlet grooves and the remainder of the grooves constituting discharge grooves, means by which unscreened pulp from the casing inlet is delivered to the inlet grooves, means providing communication between the discharge grooves and the screened pulp outlet, the other of said screen members having an opening communicating with said clearance space, and means to produce relative rotation between said screen members about their common axis, whereby said opening will be brought periodically into registry with each inlet groove.

5. A pulp screen comprising a casing having an inlet for unscreened paper pulp and a screened pulp outlet, two concentric cylindrical screen members within the casing and presenting between them a clearance space of sufficient size for the fine acceptable portion of the unscreened pulp to pass therethrough but of insufficient size for the coarse unacceptable portion of such pulp to pass therethrough, the outer screen member having in its inner face a plurality of parallel grooves, the alternate grooves constituting inlet grooves and the other grooves constituting discharge grooves, means providing a communication between the casing inlet and the inlet grooves by which unscreened pulp is delivered to said grooves, means providing communication between the discharge grooves and the screened pulp outlet, said inner screen member having an opening communicating with said clearance space, and means to rotate the inner member relative to the outer member.

6. A pulp screen comprising a casing having an inlet for unscreened paper pulp and a screened pulp outlet, pulp-screening means within said casing comprising two concentric cylindrical screen

members separated by a clearance space of sufficient width for the acceptable portion of the unscreened pulp to pass therethrough but of insufficient width for the coarse unacceptable portion of the pulp to pass therethrough, the outer of said screen members having in its inner face a circumferential row of vertically extending grooves and also having a pair of circumferential chambers, one of which is an inlet chamber and the other of which is a discharge chamber, the alternate grooves of said row communicating with the circumferential inlet chamber and the other grooves of the row communicating with the circumferential discharge chamber, means to deliver pulp from the casing inlet to the inlet chamber, and means providing communication between the discharge chamber and the screened pulp outlet.

7. A pulp screen comprising a casing having an inlet for unscreened paper pulp and a screened pulp outlet, pulp screening means within said casing comprising two concentric cylindrical screen members separated by a clearance space of sufficient width for the acceptable portion of the unscreened pulp to pass therethrough but of insufficient width for the coarse unacceptable portion of the pulp to pass therethrough, the outer of said screen members having in its inner face a plurality of circumferential rows of vertically extending grooves and also having a pair of circumferential chambers for each row of grooves, one chamber of each pair being an inlet chamber and the other being a discharge chamber, the alternate grooves of each row communicating with the corresponding circumferential inlet chamber and the remaining grooves of each row communicating with the corresponding circumferential discharge chamber, means to deliver unscreened pulp from the casing inlet to the various circumferential inlet chambers, and means providing communication between the various discharge chambers and the screened pulp outlet.

8. A pulp screen comprising a casing having an inlet for unscreened paper pulp and a screened pulp outlet, pulp screening means within said casing comprising two concentric cylindrical screen members separated by a clearance space of sufficient width for the acceptable portion of the unscreened pulp to pass therethrough but of insufficient width for the coarse unacceptable portion of the pulp to pass therethrough, the outer of said screen members having in its inner face a plurality of circumferential rows of vertically extending grooves and also having a pair of circumferential chambers for each row of grooves, one chamber of each pair being an inlet chamber and the other being a discharge chamber, the alternate grooves of each row communicating with the corresponding circumferential inlet chamber and the remaining grooves of each row communicating with the corresponding circumferential discharge chamber, the space between the casing and the outer screen member being divided by partitions into inlet and discharge passages, the circumferential inlet chambers having communication with the inlet passages and the circumferential discharge chambers having communication with the discharge passages, means providing a communication between the casing inlet and the inlet passages, and means providing communication between the discharge passages and the screened pulp outlet.

9. A pulp screen comprising a casing having an inlet for unscreened paper pulp and a screened pulp outlet, pulp-screening means within said casing comprising two concentric cylindrical screen

members separated by a clearance space of sufficient width for the acceptable portion of the unscreened pulp to pass therethrough but of insufficient width for the coarse unacceptable portion of the pulp to pass therethrough, the outer of said screen members having in its inner face a circumferential row of vertically extending grooves and also having a pair of circumferential chambers, one of which is an inlet chamber and the other of which is a discharge chamber, the alternate grooves of said row communicating with the circumferential inlet chamber and the other grooves of the row communicating with the circumferential discharge chamber, means to deliver pulp from the casing inlet to the inlet chamber, means providing communication between the discharge chamber and the screened pulp outlet, said inner screen member having openings, and means to rotate said inner screen member to bring the openings into register with the inlet grooves successively whereby each inlet groove is periodically flushed out.

10. A pulp screen comprising two opposed walls spaced from each other to provide between them a clearance space sufficient in size for the acceptable portion of unscreened paper pulp to pass therethrough but insufficient in size for the unacceptable portion of such pulp to pass, one wall having therein a plurality of separate pockets all of which open into said clearance space, means other than the clearance space for delivering unscreened paper pulp to certain of said pockets, from which the pulp flows into the other pockets through the clearance space which is common to all of the pockets, a screened pulp outlet, and means other than the clearance space providing communication between said other pockets and the screened pulp outlet.

11. A pulp screen comprising a casing having an inlet and a screened pulp outlet, pulp-screening means within the casing comprising two opposed parallel walls separated from each other by a clearance space which is substantially co-extensive with the walls and is of sufficient size for the acceptable portion of unscreened paper pulp stock to pass therethrough but insufficient in size for the unacceptable portion of such pulp to pass therethrough, one wall having therein both a plurality of inlet pockets, all of which open into said clearance space, and a plurality of discharge pockets all of which open into said clearance space, said inlet and discharge pockets having communication with each other through the clearance space, means other than the clearance space for delivering unscreened paper pulp to the

inlet pockets and means other than the clearance space providing communication between the discharge pockets and the screened pulp outlet.

12. A pulp screen comprising a casing having an inlet and a screened pulp outlet, pulp-screening means within the casing comprising two opposed parallel walls separated from each other by a clearance space which is substantially co-extensive with said walls and which is of sufficient size for the acceptable portion of unscreened paper pulp stock to pass therethrough but is insufficient in size for the unacceptable portion of such pulp stock to pass therethrough, one of said walls having therein a plurality of inlet pockets, all of which communicate with the clearance space, and also having therein a plurality of discharge pockets, all of which communicate with the clearance space, said inlet pockets and outlet pockets having communication with each other through said clearance space, means other than the clearance space for delivering unscreened pulp to the inlet pockets, means other than the clearance space providing communication between the discharge pockets and the screened pulp outlet, and means to give the two opposed walls a relative movement without varying the dimensions of said clearance space.

13. A pulp screen comprising a casing having an inlet and a screened pulp outlet, pulp-screening means within the casing comprising two opposed parallel walls separated from each other by a clearance space of sufficient size for the acceptable portion of unscreened paper pulp stock to pass therethrough but insufficient in size for the unacceptable portion of such pulp to pass therethrough, one of the walls having a plurality of inlet openings therethrough communicating with the clearance space and also having a plurality of discharge openings therethrough communicating with said clearance space, means for delivering unscreened pulp to the inlet openings, and means providing a communication between the discharge openings and the screened pulp outlet.
